UNITED STATES PATENT OFFICE.

JOHN F. DANIELS, OF DECATUR, ILLINOIS.

VAPOR-BURNER.

SPECIFICATION forming part of Letters Patent No. 258,633, dated May 30, 1882.

Application filed March 25, 1882. (No model.)

To all whom it may concern:

Be it known that I, JOHN F. DANIELS, a citizen of the United States, residing at Decatur, in the county of Macon and State of Illinois, have invented certain new and useful Improvements in Vapor-Burners, of which the following is a specification, and which has never been patented to me nor to others with my knowledge and consent in any foreign country.

My invention consists in the peculiar construction and arrangement of the generator with reference to the distributing-cap, and in the formation of the cap with reference to the flame.

In the drawings accompanying and forming a part of this specification, Figure 1 represents my device in vertical section, and Fig. 2 is a plan of the same.

20 *a* is the part that connects with the supply pipe. *b* is the generator. *c* is the connecting-pipe between the generator and orifice *d*. *e e* and *m m* are curves in the distributing-cap to direct the vapor to outlets *g g f f* without 25 making a disagreeable noise. *h* is the screw-valve that regulates the flow of vapor, and *i*

is the customary receptacle used for lighting the burner. *o o* represent core-rests on the cap.

In operation the fluid is fed into generator 30 *b*, which is located under the distributing-cap, as shown, and is broad and flat. The vapor passes through pipe *c* and orifice *d* to openings *f f g g*, where it becomes ignited.

To increase the heat, if found necessary, I 35 make a small opening in pipe *c* at *x*, and allow the flame to operate on the bottom of the generator.

I claim as new and desire to secure by Letters Patent—

40 The vapor-burner described, consisting of the flat circular generator-chamber *b* and passage *c*, leading downward and opening into the duct *d*, vapor-chamber having funnel-shaped mouth *m m*, and conical tip *e e*, extending down from above and provided with exit-openings *f g*, as set forth.

JOHN F. DANIELS.
